CLAIM

The ornamental design for an aromatherapy pillow in the form of a turtle, as shown and described.

DESCRIPTION

FIG. 1 is a perspective view of an aromatherapy pillow in the form of a turtle, taken from the front and right side, showing our new design;

FIG. 2 is a front elevational view thereof;

FIG. 3 is a right side elevational view thereof taken from FIG. 1, the left side view being the same;

FIG. 4 is a back elevation view thereof;

FIG. 5 is a top plan view thereof; and,

FIG. 6 is a bottom plan view thereof.
